P. Buckley

United States Patent Office.

PETER BUCKLEY, OF VIENNA, NEW JERSEY, ASSIGNOR TO HIMSELF AND EDWIN BULGIN, OF SAME PLACE.

Letters Patent No. 92,576, dated July 13, 1869.

IMPROVEMENT IN CHAIRS.

The Schedule referred to in these Letters Patent and making part of the same.

To all whom it may concern:

Be it known that I, PETER BUCKLEY, of the town of Vienna, in the county of Warren, in the State of New Jersey, have invented certain new and useful Improvements in Chairs; and I do hereby declare that the following is a full and exact description thereof, reference being had to the accompanying drawings, forming part of this specification, and to the letters of reference marked thereon.

The object of my invention is to utilize and bring into more valuable and important use the inner portion of the rattan cane for bottoming chairs, after the outer portion of the cane has been removed for the same purpose, for forming the seats of a certain kind of chair, known as the cane-seated chair, which is formed in a sort of lattice or open work.

It also has for its object the substitution of this material for the flag or rush so commonly used for the seat in a kind of chair known by the trade as the cottage-chair.

The nature of my invention consists in a peculiar and novel kind of loop, by which the material is secured to the frame or rims of the seat, woven and formed in such a manner as to render it perfectly secure and strong, so as to effectually resist any pressure without the loop giving way, or yielding in the slightest to the action of the pressure brought to bear upon it.

The advantages of this invention are obvious, for the reason that in the first place the material employed can be obtained at a very cheap price, say ten cents per pound, it being that portion of the rattan which is left after stripping off the outer glossy portion for making the ordinary cane-seated chair, and one pound of this material will make two seats for the ordinary cottage-chair, while the flag or rush material costs more than double that amount.

Another important advantage is, that persons of ordinary skill can make no more than four seats in a day with the flag or rush, while the same persons can make from ten to twelve per day with the material I use, which requires no paint or finish as in the case of the flag or rush seats.

I may also state that, if in a seat made after my improved method, one of the strands should be accidentally cut or broken, none of the other strands are loosened thereby.

To enable others skilled in the art to make and use my invention, I will proceed to describe its construction.

Figure I is a front elevation of a common cottage-chair, provided with my invention.

Figure II is a top-plan view of a portion of a seat, partially finished, to show the method of constructing it.

Letters of like name and kind indicate like parts in each of the figures.

D represents a chair of common construction, with my rattan or cane seat and back.

The seat and back are formed by having the ma-

terial split, or brought to a proper and convenient size.

The method of forming the loop and weaving the seat is as follows:

A strand or length of the cane, *a*, indicated by the black lines, is taken and secured to one side, *A*, of the frame, by placing one end of the strand on the under side of the frame, as seen by the dotted lines at *b*, when the loop is formed by carrying the strand a short distance transversely along the inner side of the frame; then under the frame, over the end above mentioned; then over the frame and between the frame and the transverse portion, when it is drawn tight, and a loop is thus formed.

The strand is then carried across to the other side *B* of the frame, and wound round one or more times, when another loop, as seen at *c*, is formed, after which it is again brought back to the side *A* of the frame; this process being repeated until the end of the frame is reached.

Another strand, indicated by the red lines, is then secured, in a similar manner as seen at *d* on the opposite cover of the frame, and manipulated in the same way, but in the opposite direction, by which means another strand of the warp is formed, and the vacant portions *f f* of the frame are covered.

Instead of securing the second strand, indicated by the red lines at *d*, it may be secured on the side *B* of the frame, at the corner nearest *c*, and worked in at the same time as the strand *a*, by which means both the strands forming the warp are put in, and the vacant spaces *f f* are filled as the work progresses, the loop being formed in the manner above described, except that the transverse portion is drawn over both strands of the warp at the same time.

The woof is formed by passing a strand transversely backward and forward across the frame, and alternately over and beneath the strands which form the warp.

When the whole of the seat has thus been covered, one or more separate pieces of the cane may be inserted alongside of the strands forming the warp, so as to increase the closeness of the texture.

A seat formed in this manner is exceedingly strong, neat, and durable, and possesses the advantage of being very cheap in its construction; and likewise, if one of the strands should be accidentally cut or broken, the rest of the strands will not be loosened thereby.

Having thus described my invention,

What I claim, and desire to secure by Letters Patent of the United States, is—

The method of forming the loop, and constructing the seat and back of the chair with rattan, or other material, substantially as herein shown and described, and for the purposes set forth.

PETER BUCKLEY.
